UNITED STATES PATENT OFFICE.

CLARENCE C. CHRISMAN, OF ST. LOUIS, MISSOURI.

FOLDING COPY-HOLDER FOR TYPE-WRITERS.

No. 834,262.

Specification of Letters Patent.

Patented Oct. 30, 1906.

Application filed February 19, 1906. Serial No. 301,873.

To all whom it may concern:

Be it known that I, CLARENCE C. CHRISMAN, a citizen of the United States, and a resident of St. Louis, Missouri, have invented 5 certain new and useful Improvements in Folding Copy-Holders for Type-Writers, of which the following is a specification containing a full, clear, and exact description, reference being had to the accompanying 10 drawings, forming a part hereof.

My invention relates to a folding copy-holder for type-writers; and the object of my invention is to construct a flat housing or hollow base on which the type-writer is positioned and to construct a folding adjustable 15 copy-holder which is adapted to be folded or collapsed and positioned within the housing when not in use.

A further object of my invention is to construct 20 a folding copy-holder for type-writers which may be readily positioned at any angle on either side of the type-writer and operator.

To the above purposes my invention consists of certain novel features of construction 25 and arrangement of parts, which will be hereinafter more fully set forth, pointed out in my claims, and illustrated in the accompanying drawings, in which—

Figure 1 is a plan view of my improved 30 copy-holder, the same being folded and positioned within the hollow base. Fig. 2 is a front elevation of the parts seen in Fig. 1 and a portion of a type-writer in position upon the hollow base. Fig. 3 is a plan view of the 35 copy-holder unfolded and swung to one side of the base. Fig. 4 is an enlarged vertical section taken on the line 4 4 of Fig. 1. Fig. 5 is an enlarged transverse section taken on the line 5 5 of Fig. 1. Fig. 6 is an enlarged 40 detail section taken on the line 6 6 of Fig. 3. Fig. 7 is a detail elevation showing the connection of a spring with the copy-holding plate.

In the construction of my improved copy-holder the housing or hollow base comprises 45 a bottom plate 1 and a top plate 2, which plates are approximately rectangular and of the same size, and positioned between the side edges of said plates are strips 3, which 50 do not extend all the way to the front edges of said plates.

Located between the rear edges of the plates is a strip 4, and thus a flat hollow base is formed on which the type-writer is positioned. 55

Formed in the top plate 1 and extending from the front to the rear of the center thereof is a slot 5, and extending parallel with the front edge of the top plate is a slot 6, with which the slot 5 communicates. 60

7 designates an arm that is arranged to slide in the space between the plates 1 and 2, and seated in the top side of the rear end of this arm is a pin 8, which extends upwardly through the slot 5 and is provided with a 65 head just above the top surface of the plate 2.

The forward end of the arm 7 is provided with a segmental plate 9, there being a shoulder 10 formed on top of this plate adjacent its edge, and in said shoulder is formed a series of notches 11. 70

The outer end of the plate 9 is provided with a perforated ear 12, by means of which said plate is manually engaged when the plate and arm 7 are withdrawn from the base 75 of the holder.

A portion 13 at the forward end of the arm 7 extends over the plate 9, and pivotally held between said plates 13 and 9 is a plate 14, to which is hinged a large rectangular plate 15, 80 which forms the copy-holding plate of my improved device. Rigidly fixed to the rear side of this plate 15 and extending downwardly therefrom is a leaf-spring 16, the lower end of which is adapted to engage in any one 85 of the notches 11.

A single length of wire 17 is bent into rectangular form and its ends secured together in any suitable manner, and springs 18 are formed in the sides of the rectangularly-bent 90 wire, which springs are engaged by staples 19, secured to the front face of the plate 15 adjacent its sides. The tendency of these springs 18 is to press the ends of the rectangularly-bent wire 17 onto the ends of the plate 15, 95 and thus retain in position on said plate 15 a book or sheet containing notes or matter that is being transcribed by the stenographer using the machine located on the hollow base. 100

When the device is folded and out of use, the copy-holding plate 15 is swung upon its hinge, so that it lies face downwardly upon the arm 7, as seen by dotted lines in Fig. 3, and said plate and arm are now moved inwardly between the plates 1 and 2, and in so doing the pin 8 moves to the rear end of the slot 5. Thus said parts are in an out-of-the-way position while not in use. 105

To bring the copy-holder into use, the op- 110

erator engages the perforated ear 12 and pulls forwardly to bring the arm 7 and parts carried thereby forwardly from between the plates 1 and 2.

5 When the pin 8 passes from the forward end of the slot 5 into the slot 6, the plate 15 is elevated, and at the same time the arm is swung around to the side in either direction and moved along to the side of the hollow base, with the pin 8 traveling in the slot 6.

When the arm 7 is moved at right angles to the front edge of the base, one side of said arm will bear against the forward end of the corresponding one of the strips 3.

15 The plate 14 is now moved upon its pivot so as to swing the plate 15 around into position where it can be readily seen by the operator of the machine, and the lower end of the leaf-spring 16 is engaged in one of the notches 20 11 to lock the plate 15 in proper position.

The book or sheet containing the notes to be transcribed or copied is now inserted beneath the ends of the spring 17 and is thus held in a position convenient to the operator.

25 The copy-holding plate 15 can be adjusted laterally relative to the hollow base by moving the arm 7 outwardly or inwardly to the proper point, and in so doing the pin 8 travels through the corresponding portion of the slot 6.

30 A copy-holder of my improved construction is simple, easily opened or folded, holds the work on either side of the operator, and the housing thereof forms a substantial base 35 on which the type-writer is positioned.

When not in use, the copy-holding plate is folded into an out-of-the-way position, and

therefore does not take up any room on the desk or table adjacent the type-writer.

I claim—

1. In a copy-holder for type-writers, a hollow base, and a copy-holding plate arranged to slide in said base; substantially as specified. 40

2. In a copy-holder for type-writers, a hollow base, an arm arranged to slide therein, and a copy-holding plate carried by said arm; substantially as specified. 45

3. In a copy-holder for type-writers, a hollow base, an arm arranged to slide therein, and an adjustable copy-holding plate hinged to the outer end of said arm; substantially as specified. 50

4. In a copy-holder for type-writers, a hollow base, an arm arranged to slide therein, a hinged copy-holding plate pivotally connected to the outer end of the arm, and a copy-holding spring arranged on the face of the copy - holding plate; substantially as specified. 55

5. In a copy-holder for type-writers, a hollow base, an arm arranged to slide therein, a hinged copy-holding plate pivotally connected to the outer end of the arm, and means whereby said plate is locked at various 60 positions on said arm; substantially as specified. 65

In testimony whereof I have signed my name to this specification in presence of two subscribing witnesses.

CLARENCE C. CHRISMAN.

Witnesses:

M. P. SMITH,
JOHN C. HIGDON.
